UNITED STATES PATENT OFFICE

FRANK S. TRUMBULL, OF PROVIDENCE, RHODE ISLAND

DESIGN FOR A SIPPER SPOON

Application filed January 22, 1931. Serial No. 38,416. Term of patent 7 years.

To all whom it may concern:

Be it known that I, FRANK S. TRUMBULL, a citizen of the United States of America, residing at Providence, county of Providence, State of Rhode Island, have invented a new, original, and ornamental Design for a Sipper Spoon, of which the following is a specification, reference being had to the accompanying drawing, forming a part thereof.

Fig. 1 is a front elevation of a sipper spoon, showing my new design; Fig. 2 is back view, and Fig. 3 is a side view of the same.

I claim:

The ornamental design for a sipper spoon, substantially as shown.

FRANK S. TRUMBULL.
